Primary Examiner — Sandra S Snapp*Assistant Examiner* — Mehri F Bajoul(74) *Attorney, Agent, or Firm* — Thomas A. O'Rourke; Bodner & O'Rourke, LLP(57) **CLAIM**

The ornamental design for a toy disk, as shown and described.

DESCRIPTION

FIG. 1 is a front perspective view of a toy disk showing the new design;

FIG. 2 is a top view thereof; and,

FIG. 3 is a side view thereof.

The criss-cross pattern of lines shown in the drawings represent material that is understood to be distributed uniformly over the associated surface of the disk.

The broken lines in the drawings depict the boundaries of the claim and form no part of the claimed design.
